L. HONIGMANN ET AL.

REVOLVING RING OVEN

Filed June 2, 1926

UNITED STATES PATENT OFFICE.

LUDWIG HONIGMANN, OF BAD TOLZ, AND FRIEDRICH BARTLING, OF MUNICH,
GERMANY.

REVOLVING-RING OVEN.

Application filed June 2, 1926, Serial No. 113,289, and in Germany June 3, 1925.

The arrangement of revolving ring ovens such as are used for the drying and the dry distillation of granular or pulverulent materials is generally known. In substance such ovens generally comprise a ring shaped muffle built up of refractory stone within which is arranged for rotation a rotary ring which acts as a hearth and receives the material to be treated.

10 The object of the invention is to provide a novel arrangement of such a furnace, which presents material advantages over previously known arrangements. The aim is to build the oven in all its essential parts of iron, thereby effecting considerable economy both in cost and labour as compared with the usual stone ovens, and at the same time facilitating the erection and dismantling of such ovens so as to enable the same to be readily moved 15 from place to place without much trouble and substantial foundations.

20 In order to attain this object according to this invention, the whole oven is constructed as a suspension oven. Accordingly the annular muffle is suspended from a carrier frame of the simplest type. The revolving ring hearth closing the lower opening of the muffle is carried by a carousel-like rotary support, the effect of all this being that an oven 25 of this kind may be constructed at extremely small cost, and can be quickly assembled and disassembled.

The foundation comprises merely appropriate foundation blocks forming the supports for the carrier frame and for the journal of the carousel, which latter as a rule, is constructed in the form of a so-called king pin.

If the ring hearth is to be provided with heating from below, this can be easily effected by equipping the ring with a channel shaped cavity to which the heating agent is supplied from the centre of the oven by way of a swinging pipe. In order to enable the condensate 40 separate from the heating medium to be removed, use is made, according to the invention, of a stationary ring shaped trapping trough revolving below the ring and in which are discharging sockets for the condensate. 45 The oven cover, according to this invention, is made by preference with double walls of iron with the interposition of an insulating layer 50 between the walls. An oven cover of this kind

is cheap and yet fully capable of replacing a bricked arching. 55

A constructional form of the invention is diagrammatically illustrated by way of example in the annexed drawing in sectional elevation.

The oven comprises a suspension frame A composed of simple girders and provided with supporting arms *a* which rest on supports *b* which are anchored in foundation blocks *c*. Suspended from each carrier arm at a suitable distance are two bolts *d*, and suspended from these is the ring shaped oven muffle *E*. The latter consists of a double walled cover *e*, *e'* connected to which in downward direction are lateral cheeks *f*, *f'*. Between the walls *e*, *e'* is a space which is filled with insulating material *g*. Arranged at a suitable point in the cover is an outlet *h*. The downwardly open muffle is close against the revolving ring *l* which rests on a carousel-like support *j*. The latter comprises a so-called 'king pin' *i* provided with radial arms *k* on the ends of which the ring hearth *l* is carried. The rotation of the king pin *i* is effected by a gear of the usual kind, for example, a worm gear *m*. The ring hearth *l* has its top face provided with a cavitated surface *l'* for the reception of a thin layer of the charge. It is constructed as a hollow body so as to provide a channel shaped heating chamber *n* which laterally may be confined by insulating layers *n'*, *n''*. The lateral cheeks *f*, *f'* of the muffle are by preference trough shaped to form cooling troughs which receive lateral ribs *o* of the ring *l*. The sealing within these troughs is effected by sand or a cooling 75 liquid. 80

The admission of the heating agent, for example, steam to the heating chamber *n*, is effected by a swing pipe *p* which revolves with the ring *l*, and by preference may be journalled in one of the arms *k*. In the centre of the oven the swing pipe *p* is in communication with a stationary conduit *q* which may be journalled in the suspension structure. Provision may be made also of an appropriate 85 exhaust pipe for the heating agent, and of means for drawing off the condensed water of the heating steam. To this end a stationary trough *r* is arranged beneath the ring revolving in which are discharge pipes *s* leading from the heating chamber *n*. 90 100 105

Having now particularly described and ascertained the nature of our said invention and in what manner the same is to be performed, we declare that what we claim is:—

- 5 1. In a rotary ring hearth oven, a stationary supporting structure, a ring shaped muffle suspended therefrom and having an open underside, a hearth rotatable relative to said muffle and forming a closure for its under-
10 side, said hearth having a heating chamber beneath the same, a rotary support for said hearth rotating about a center concentric to said muffle, a pipe for supplying a heating medium to said chamber rotatably supported
15 by said stationary supporting structure and movable about a center coincident with the center of rotation of said rotary support, other pipes depending from said heating chamber for discharging condensate therefrom,
20 and a stationary ring shaped trough below said other pipes into which said condensate is discharged.
2. In a rotary ring hearth oven, a supporting structure, a ring shaped muffle suspended therefrom and including a cover consisting of spaced metallic walls, a heat insulating medium between said walls, a rotating hearth supported for rotation below said muffle, and means for rotating said hearth.
3. In a rotary ring hearth oven, a supporting structure, an oven body including a ring-shaped muffle constituted by a cover and side members depending therefrom, means for suspending said cover and side members entirely from said supporting structure, a rotating hearth supported for rotation below said muffle and between said side members, and means for rotating said hearth.
4. In a rotary ring hearth oven, a support-

ing structure, an oven body including a ring-shaped muffle constituted by a cover and side members depending therefrom, means for suspending said cover and side members entirely from said supporting structure, a rotating hearth supported for rotation below said muffle and between said side members, a supporting member for said hearth extending inwardly therefrom in a radial direction to a point coincident with the center of rotation of said hearth, a pivot about which said supporting member revolves, and means to revolve said hearth-supporting member.

5. In a rotary ring hearth oven, a supporting structure, an oven body including a ring-shaped muffle constituted by a cover and side members depending therefrom, means for suspending said cover and side members entirely from said supporting structure, a rotating hearth supported for rotation below said muffle and between said side members, said hearth having a heating chamber beneath the same, a supporting member for said hearth extending inwardly therefrom in a radial direction to a point coincident with the center of rotation of said hearth, a pivot about which said supporting member revolves, means to revolve said hearth-supporting member, and a pipe for supplying a heating medium to said chamber, said pipe having one end rotatably mounted in said supporting structure above said pivot and being movable with said rotatable supporting member.

In testimony whereof we have signed our names to this specification.

LUDWIG HONIGMANN.
FRIEDRICH BARTLING.
